UNITED STATES PATENT OFFICE.

JOHN C. KASSENER, OF MANITOWOC, WISCONSIN.

ARM-SLING.

1,266,688.

Specification of Letters Patent. Patented May 21, 1918.

Application filed February 22, 1918. Serial No. 218,328.

To all whom it may concern:

Be it known that I, JOHN C. KASSENER, a citizen of the United States, and resident of Manitowoc, in the county of Manitowoc and State of Wisconsin, have invented certain new and useful Improvements in Arm-Slings; and I do hereby declare that the following is a full, clear, and exact description thereof.

10 My invention relates broadly to improvements in invalid apparel, more particularly to arm supports or the like.

It is well known that during the healing of injured arms it is customary to support 15 the same in an elevated position by means of a sling suspended from about the person's neck. When the sling is so supported its use obviously becomes tiresome to the wearer after a considerable period of time due to 20 the strain on the neck. With the idea of eliminating this objectionable feature of ordinary arm supports, I have devised the present invention which consists of a sling in which the strains incident to the weight 25 of the person's arm are evenly distributed upon both shoulders and back.

It is a further object of my invention to provide a simply constructed sling which can be readily and quickly placed on the 30 wearer's body without assistance.

With these and other objects in view the invention consists in the novel features of construction and arrangement of parts which will be hereinafter more particularly 35 described and claimed and shown in the drawing wherein:

Figure 1 represents a plan view of a garment constructed in accordance with my invention, and

40 Fig. 2 is a general perspective view of the device in operation.

Referring more particularly to the drawing it will be seen that the invention comprises a garment preferably formed from a 45 single sheet of material, such as readily washable cloth. The sheet is elongated being substantially two and a half times as long as its average width and is provided intermediate its ends with a horizontal opening 1 of appropriate size. The portion of the sheet between this opening and one end forms a back engaging part 2, while the other end portion provides a combined front part and arm support 3.

55 When in use the intermediate portion 4 of the sheet immediately surrounding the

opening 1 rests upon the wearer's shoulders as shown in Fig. 2, the portion 2 engaging the back and the portion 3 the front of the wearer. These front and back portions have their edges connected together to form a vest like garment as shown in the last mentioned figure. Said edges are detachably and adjustably connected by means of hooks and eyes 5 and 6 respectively.

The hooks 5 are carried by buckles 7 which are adjustably disposed on straps 8 which extend laterally and at right angles to the longitudinal axis of the sheet as shown in Fig. 1. These straps, two of which project from each side edge of the portion 2 are located adjacent the free end thereof and form a continuation of tabs 9. The eyes on the other hand, are secured to tabs 10 which extend from the opposite edges 75 of the sheet and intermediate the ends of the portion 3. Said tabs 9 and 10 when the device is in use are disposed immediately below the arm pits of the wearer as shown.

After the sheet has been arranged on the user as just set forth, the free end portion of the part 3, which depends downwardly in the form of an apron, is folded upon itself to provide the sling for the arm or arms of the invalid. The free end of this 55 part 3 has a plurality, preferably three, of eyes 11 secured thereto which cooperate with hooks 12 when the part 3 is folded. The hooks are carried by buckles 13, the same being secured to depending straps 14 on that are set or otherwise secured to the intermediate portion of the sheet. One of the straps is disposed on each side of the opening 1, while the other is secured adjacent the front end of said opening. Owing 60 to the adjustable nature of the hooks 12 it is obvious that the bottom of the sling may be raised or lowered to accommodate the same to the user's injured arm. Similarly one side or end of the sling may be elevated or lowered above or below the other.

The adjustability of the device permits the same to be used on persons of various sizes without any change in the dimension of the sheet of material forming the major part of the invention. Also the construction of the sling allows it to be readily used to support either or both arms as the case may be.

Having thus described my invention what I claim as new is:

1. A sling of the nature described comprising

- ing a sheet of material having a head opening in its intermediate part, said intermediate part being adapted to rest upon the user's shoulders, said sheet including a back engaging portion, a front portion, an arm support carried by the front portion, and means for detachably connecting the edges of said front and back engaging portions below the arm pits of the wearer. 5
- 10 2. A sling of the class described comprising a sheet of material having a head opening in its intermediate part, said intermediate part being adapted to rest upon the user's shoulders, said sheet including a back engaging portion, a front portion, means for detachably connecting the edges of said
- front and back engaging portions below the arm pits of the wearer, said front portion being of greater length than the back engaging portion and folded transversely 20 mid-way its ends below said edge connecting means, and means for detachably securing the free end of the front portion to the main part thereof adjacent said edge connecting means whereby to form an arm support open at its opposite ends. 25

In testimony that I claim the foregoing I have hereunto set my hand at Manitowoc, in the county of Manitowoc and State of Wisconsin.

JOHN C. KASSNER
